ATTORNEY

UNITED STATES PATENT OFFICE

FRANZ S. BURTON, OF KANSAS CITY, MISSOURI

TRUSS

Application filed November 23, 1928. Serial No. 321,287.

My invention relates to hernia trusses, and more particularly to trusses for supporting areas at the groin of the wearer, the principal objects of the invention being to provide for 5 automatic adjustment of a truss pad to the groin and to an area to be supported, to mount a non-circular pad rotatively and removably on a belt, and to facilitate the mounting, replacement and positioning of truss pads.

10 In accomplishing these and other objects of the invention, I have provided improved details of structure, the preferred forms of which are illustrated in the accompanying drawing, wherein:

15 Fig. 1 is a perspective view of a double truss embodying my invention.

Fig. 2 is an enlarged detail perspective view of a truss pad and pad support separated, a belt and crotch strap being shown fragmentarily.

20 Fig. 3 is a vertical central section of the support and pad rotatively attached thereto by a snap fastener.

Fig. 4 is an enlarged vertical central section of the snap fastener with the parts in separated position.

Referring in detail to the drawing:

1 designates a belt formed preferably of flexible and elastic material, 2 a loop member 30 adjustably mounted on the belt, and 3 a hook fixed to the belt and adapted to latch in the loop.

Crotch straps or bands 4 of elastic material have loops 5 at one end sleeved on the 35 belt and provided with slides 6 for adjusting the lengths of the straps to fit the wearer. The opposite ends of the straps extend upwardly over the inner face of the belt, then downwardly over the outer face thereof and 40 their extremities are attached to the body portions of the straps as at 7, thus forming loops 8 slideable over the belt, and adapted as presently described to support truss pads 9 and 10.

45 Because of the novel character and mode of operation of my truss pads, I may provide a double truss when a single area is to be treated, the pad 9 representing that which is to serve the hernia, and a supplemental 50 smaller pad 10 being provided for the other

groin to balance the truss and to support an uninjured area to prevent development of a hernia therein. The pads and supports are similarly formed and supported and but one assembly will be particularly described.

55 The pad 9 comprises a body 11 of light weight, resilient material, preferably sponge rubber, and as especially adapted for mounting by my improved means, is non-circular, elongated, with a flat rear surface 12, and a convex front surface 13, having a relatively thick portion 14 adjacent one end.

I contemplate mounting the pad removably and rotatively on the belt, for example by snap fasteners, and in order to support one member of the snap fastener from the pad I attach a relatively strong facing member 15 to the body 11, and since the pad is adapted to rotate and bear against the belt, the member 15 is formed of smooth material adapted to 60 resist wear, for example leather, and mount the stud member 16 of a snap fastener in the facing member 15. The stud member 16 comprises a cylindrical body 17, and parallel 65 radial flanges 18 and 19 spaced sufficiently to receive the edge of the leather facing member 15 at an opening 20 provided therein to receive the snap fastening member.

70 As illustrated and preferred, the facing member 15 is attached to the body 11 by a cover 21 of soft material such as cloth which extends over the convex surface of the body 11, and is attached to the facing member by stitching 22 after the snap fastening member 16 has been installed in the opening 20.

75 The complementary socket member 23 of the snap fastener is secured to the loop portion 24 of a crotch strap which overlies the inner face of the belt.

To facilitate the operation of the rotative pad, assure its effective functioning, and protect the belt, I provide a backing plate or pad-mounting circular bearing disk 25, comprising a relatively soft and resilient body 26 which may be formed of the same material as the belt, and a smooth, relatively thin facing member 27 adapted to resist wear and consisting preferably of tough material such as leather, and attach the disk to the crotch strap loop by the snap fastening socket mem- 80

ber 23. In the preferred construction, a rivet 28 is mounted in registering openings 29 and 30 in the strap portion 24 and center of the disk 25, the head 31 of the rivet engaging the outer surface of the strap portion 24. The socket member comprises a disk-like body 32 mounted on the end of the rivet and engaging the facing member 27 of the disk 25, the peened end 33 of the rivet latching the disk to the strap; and a resilient outwardly converging annular wall 34 comprising the socket in which the stud member 16 is engaged for rotatively supporting the pad from the belt.

15 The elastic belt and crotch straps tend to yield under movements of the wearer, to prevent displacement of the pad.

20 The fastening means is preferably adapted to space the pad slightly from the backing member to facilitate free rotation of the pad, and the spacing may be varied, for example by increasing the thickness of the backing disk, or varying the lengths of the cylindrical members of the snap fastener or like 25 mounting means.

30 The pads are illustrated as positioned with their wider and thicker portions at the top, but may be reversed to suit the preference of the wearer, and will operate as described in reversed position.

35 Pads of different shapes and sizes and equipped with mounting means such as the members of a snap fastener, may be provided for mounting rotatively on a belt provided with complementary supporting elements, and particularly provided with the backing plates or disks, and a new pad may be substituted easily for one found unsatisfactory or when conditions change, without 40 necessity for supplying a complete new truss.

45 In applying and using a truss of the character described, a pad of suitable size and shape for the condition and position of the hernia is selected, and a smaller pad may also be selected for application to the other groin. The pad may be adjusted laterally and rotatively both before and after the belt is fastened.

50 Attention is particularly called to the structure whereby the pad may be rotated on its support, so that an elliptical, oval or other non-circular pad, and a pad having greater thickness or depth at one point than another, may be moved rotatively to fit it accurately to 55 the anatomy of the wearer and the area to be served, and thus assure and enhance the desired supporting effect of the pad, obviate hazard of injury, and promote the comfort of the wearer.

60 A pad rotatively supported as described has the further important advantage that it will automatically move rotatively to proper hernia-supporting position, in relation to the 65 groin, should it be inaccurately positioned when applied and will not be displaced by the

movement of the belt and strap due to motions and changes of attitude of the wearer. In this respect my invention improves particularly on flat pads, and others, that are fixed to a belt or crotch strap, and tend to be moved partly away from supporting position when the wearer changes his posture.

70 Attention is further called to the service of the backing disk having diameter substantially equal to and preferably slightly less than the longest dimension of the pad, which provides a relatively wear-resistant and smooth surface over which the portions of the tilted pad may slide for facilitating rotation, and which protects the crotch strap and 75 belt from frictional contact by the tiltable and rotatable pad.

80 Since a pad of this character is automatically adjusted to proper position at the groin, a supplemental pad will be the more readily 85 added, and the wearing of proper corrective as well as preventive pads will be promoted.

What I claim and desire to secure by Letters Patent is:

90 1. A truss including a support, a non-circular pad having a plane inner face and a stud projecting from said face, a backing member mounted on the support and comprising a disk having diameter substantially equal to the longest dimension of the inner face of said pad, and a socket mounted centrally in said backing member to receive said stud for rotatively mounting the pad on the backing member, and having a rim projecting above the 95 surface of said disk to engage said pad to permit portions of the inner face of the mounted pad to engage the disk under pressures consequent on use of the truss.

100 2. In a truss including a support and a pad, a socket member fixed against rotation to the support, a stud fixed to the pad to engage in said socket member for rotatively mounting the pad on the support, means including a rim portion of said socket and a flange on 105 said stud engageable with said rim portion for spacing the pad from the support, and a disk mounted on the socket member and fixed against rotation thereto and having less thickness than the space between the pad and the support to normally space the adjacent 110 faces of the pad and the disk and having a diameter substantially as great as the longest dimension of the pad.

115 3. In a truss including a belt and a pad having a flat face, means including a strap mounted on the belt for supporting the pad, means for rotatively mounting the pad on the strap and including means for spacing the flat face of the pad from the strap, and a 120 backing plate fixed to the strap between the pad and the strap and comprising a body having less thickness than the space between the pad and the strap and a facing member on the body forming a wear-resisting surface to engage portions of the flat face of the pad.

4. A truss comprising a belt, a strap having a loop slideable on the belt, a stud fixed to the loop, a cylindrical socket mounted on the stud and having substantial length for
5 spacing the rim of the socket outwardly from the stud, a pad comprising a non-circular body having a flat inner face and a wear-resisting facing member on said face, a stud fixed to the pad in the center of the facing
10 member and projecting a substantial distance from said member to engage in said socket for tiltably and rotatively mounting the pad on the loop, a flat faced circular disk having diam-

eter substantially equal to the longest dimension of the facing member and provided with a center opening for mounting the disk on the first named stud, and having thickness substantially equal to the length of said stud for
70 spacing the face of the disk from the facing member of the pad, and a wear-resisting facing member on the disk forming a bearing surface for frictional engagement with portions of the facing member of the pad when
75 the pad is tilted.
